Des. 232,323
Patented Aug. 6, 1974

232,323

COIL WINDER

Raymond F. Kimball, Arcadia, Calif., assignor to Eubanks
Engineering Co., Monrovia, Calif.

Filed Dec. 19, 1972, Ser. No. 316,590

Term of patent 14 years

Int. Cl. D15—09

U.S. Cl. D55—1 F

FIG. 3.

FIG. 1 is a perspective view of a coil winder showing my new design;

FIG. 2 is an elevational view of the side opposite that seen in FIG. 1; and

FIG. 3 is a rear elevational view of the same.

I claim:

The ornamental design for a coil winder, as shown.
